UNITED STATES PATENT OFFICE.

GERHARDT E. GRIMM, OF NEW YORK, N. Y.

ORNAMENT FOR CHRISTMAS TREES OR THE LIKE.

Application filed January 3, 1922. Serial No. 526,749.

To all whom it may concern:

Be it known that I, GERHARDT E. GRIMM, a citizen of the United States, and resident of New York city, in the county of New 5 York and State of New York, have invented certain new and useful Improvements in Ornaments for Christmas Trees or the like, of which the following is a specification.

This invention relates to a pendant ornament and more particularly to a pendant ornament for use as a Christmas tree decoration or the like; and has special reference to the provision of an ornament of this nature which combines the features of low 10 cost of production, efficient and low cost of handling and marketing and unique convenience in use and re-use and which forms an attractive, highly pleasing, variegated Christmas tree display unit.

20 Among the various forms of Christmas tree ornaments suggested previously and in use at the present time, the form most commonly marketed and used is that comprising a vitreous shell or ball. As is well known great care must be taken in the manufacture, 25 packing, shipping and marketing of these balls in view of the excessively fragile character of this type of ornament. These vitreous ornaments must be packed with caution, 30 and where the ornaments are packed in quantities as is usual, special containers or cartons with separating compartments must be utilized, in conjunction with shock absorbing packing material, the cost of pack- 35 aging being a factor reflected in the ultimate selling price of the product. These glass balls consume, furthermore, considerable space, with the result that shipping or trans- 40 portation costs thereon are relatively large, with the ultimate selling price of this commodity enhanced thereby. These shells must also be handled with considerable care during the marketing thereof, the loss in 45 breakages being considerable during sale, as is well known. In view of their fragile character, the ornaments are troublesome to handle during decorative use, the frailty and size of the balls requiring, furthermore, careful and special storage when it is de- 50 sired to store the ornaments away for use.

on successive Christmas holidays. To provide or produce a Christmas tree ornament in which are embodied the advantageous features of display with the display features rendered in many respects more attractive, 55 and in which the aforementioned disadvantages incident to the manufacture, sale and use of the glass ornaments are successfully eliminated, constitutes a prime desideratum of my present invention.

The principal objects of my present invention may be said to include the provision of a pendent ornament adapted for Christmas tree decorations or the like, which may be made to assume various three dimensional 60 forms and which ornaments may be collapsed to be packageable in small confines, —one form of my invention contemplating the collapsibility of the ornament to a substantially two dimensional or flat condition, 65 rendering the same subject to inexpensive packing operations, cheap transportation rates, convenient and inexpensive handling, marketing and storing and the further provision of an ornament of the nature referred 70 to which may be produced at low cost and which will provide a variegated, highly attractive ornamental display.

To the accomplishment of the foregoing and such other objects as may hereinafter 75 appear, my invention consists in the elements and their relation one to the other, as hereinafter particularly described and sought to be defined in the claims, reference being had to the accompanying drawings 80 which show preferred emodiments thereof, and in which:

Figures 1 to 5 show one form of my invention, Figures 1 and 2 showing the ornament in flat or collapsed condition, Figures 90 3 and 4 showing the manner of moving the parts of the ornament from collapsed to open condition, and Figure 5 being a perspective view showing the ornament in "open" position assuming a three dimensional configuration.

Figures 6 and 7 are views of a modification of my invention, Figure 6 showing the ornament in collapsed condition and Figure 100 7 showing the same in "open" position,

Figures 8 and 9 are views of a still further modification, Figure 8 being a view of the same in collapsed condition and Figure 9 being a view of the same in "open" condition, and

5 Figure 10 is a perspective view of a still further modification.

As hereinbefore referred to, a prime object of my present invention comprehends 10 the provision of an ornament which may be made to assume a three dimensional configuration when desired for decorative use and which may be collapsed to small confines and in some forms of my invention to 15 a substantially two dimensional condition when not in use, as during the marketing or storing period thereof. To this end my invention contemplates a pendant ornament comprising a plurality of surface sections of 20 a three dimensional object, the said surface sections being positionable or movable about a common axis to obtain a three dimensional configuration such as a sphere or an ellipsoid, for example, the surface sections being 25 movable from such positions to collapsed condition. Referring now to Figures 1 to 5 of the drawings, which show one form my invention may take, the ornament comprises a plurality of surface sections 11, 12, 30 13, 14, 15 and 16, the said sections in the present exemplification of my invention being fashioned or cut substantially in the form of lunes of a sphere. The sections or lunes 11 to 16 are made of a flexible ma- 35 terial such as relatively heavy paper, paper board or the like, the same being capable of being flexed and moved from a collapsed condition as shown in Figure 1 of the drawings, to an opened condition as shown in 40 Figure 5 of the drawings.

The surface sections 11 to 16 may be sold separately and connected together for use by the decorator, it being preferred, however, that the surface sections be connected 45 together and sold as a unit in condition ready to be "set up" or "opened up" by the decorator. To this end each of the sections or lunes is provided with orificed lobe portions at the opposite ends thereof, lune 11 50 being provided, for example, with the lobe portions 11' and 11², the remaining lunes 12 to 16 inclusive being similarly provided with the lobe portions 12', 12², 13² and 14' to 16² inclusive and through these orificed lobe portions is threaded a cord or string 55 17, the said string providing an axis about which the lune sections are movable, the said string 17 further providing means for suspending the ornament on some suitable 60 support, as the branches of a Christmas tree, as will be apparent. For the purpose of securing the lobes together means such as eyelets 18 and 19 may be provided. The surface sections 11 to 16 are adapted to be flexed 65 in a manner as shown in Figure 3, as will

appear further presently, and to the end of holding the surface sections in any desired flexed position a resilient holding means 20 is provided, the said holding means comprising preferably a piece of soft 70 rubber suitably orificed for receiving the string 17 and movable along the same, the said resilient holding means being effective when moved along string 17 for retaining the sections 11 to 16 in any flexed position. 75

Normally the parts of the ornament are arranged in the flat, as shown in Figures 1 and 2 of the drawings, with the lunes in overlying relation and the ornament is so packaged and sold. When it is desired to 80 "open" the ornament and condition the same for decorative use, the string 17 is taken hold of at its suspending end and the soft rubber holding means 20 is moved along the string, causing the lunes to assume the flexed 85 positions as shown in Figure 3 of the drawings. The lunes or surface sections 11 to 16 are then separated and moved to spaced positions about the axis defined by the string 17 and to the end of facilitating movement 90 of the surface sections, each surface section is provided preferably with a pulling tab such as 21. Figure 4 of the drawings shows the innermost surface section being withdrawn from the other surface sections in 95 the process of "opening" the ornament. All the surface sections 11 to 16 are then moved in their relatively spaced positions until the ornament assumes, for example, a spherical 100 form, as shown in perspective in Figure 5 100 of the drawings. If it is desired to form an ellipsoidal or oval configuration instead of a spherical configuration, any number less than the full number of lunes may be opened up as, for example, four or five lunes, the holding member 20 being moved along the string 17 to effect a lesser degree of flexing of the lunes, the shape of the three dimensional object being varied in this manner. 105

For the purpose of providing a colored and a variegated ornament, the surface sections 11 to 16 are preferably faced with colored metal foil and the various faces preferably differently colored. These sections 11 to 16 may be faced with metal foil of the following colors respectively: red, blue, yellow, green, yellow, purple. Adjacent sections are preferably differently colored as indicated, this construction providing a highly pleasing, variegated ornament when the same is rotatably suspended on a support by means of the string 17. 110

115 Referring now to Figures 6 and 7 of the drawings, I show another form my invention may take, this form of my invention contemplating the provision of concentrically arranged members comprising inner and outer sections. In this form of my invention instead of providing the surface sections in the form of lunes, I preferably 120 125 130

make opposite lunes integral so that the same may assume a ring or hooped shaped condition. To this end, as shown in Figures 6 and 7, the inner section is provided 5 with concentric hoop members 21' and 22 and the outer section with concentric hoop members 23 and 24 respectively, each hoop member comprising opposed lune sections, as clearly appears in Figure 7 of the drawings. The inner hoop members are connected together preferably by means of the eyelets 25 and 26, the outer hoop members being connected together by the eyelets 27 and 28, the inner and outer hoop members 15 being relatively concentrically spaced by means of the spacing tubes 29 and 30, all the parts being secured together by means of the securing strings 31 and 32 respectively, suitably knotted at opposite ends, and held 20 in position by means of suitable washers 33. The string 31 preferably forms the suspending element for the ornament. The hoop members may be suitably colored as in the other form of my invention, this being particularly shown in Figure 7 of the drawings. Figure 6 shows the arrangement of the parts in collapsed condition, the hoops being here shown in overlying relationship and collapsed to relatively small confines. When it 25 is desired to open the ornament, the outer and inner hoops are moved to spaced positions in planes normal to each other, as clearly shown in Figure 7. In this form of my invention, although the surface sections 30 are not collapsible to the flat as in the form shown in Figures 1 to 5, the hoop members may be moved to opened position with somewhat greater facility.

Referring now to Figures 8 and 9 of the 40 drawings, I show a still further modification of the invention in which the surface sections also comprise concentric hoop members 34, 35 and 36 provided with colored metallic foil faces to effect a variegated ornament, the said hoop members comprising opposite lune portions collapsible to hooped condition, as shown in Figure 8 of the drawings, and movable to open condition as shown in Figure 9 of the drawings. In this 45 form of my invention the hoop members may be connected together at their opposite ends by means of the eyelets 37 and 38, through which is threaded the string 39 forming the axis of the suspending element, suitable holding members made of soft rubber or the like such as 40 and 41 being provided for holding the hoops in proper ring 50 shape condition.

In Figure 10 of the drawings I show a 60 further modification of my invention in which the surface sections are provided with transparent portions forming windows. To this end each of the sections such as 11^a, 12^a, 13^a, 14^a, 15^a and 16^a is provided with ornamental transparent windows 42, which may

be made of celluloid or other flexible transparent or translucent material. This ornament may comprise a luminous display and to this end I may suspend within the ornament a low power electric bulb 43, the said bulb being hung from the holding means 70 20^a, wiring to the bulb being led through the suspending means 17^a.

The manner of making and using my novel ornament will be apparent from the above 75 detailed description thereof. In each form of my invention the ornament may be collapsed to small confines and in the form shown in Figures 1 to 5 the same may be collapsed to assume a condition in the flat 80 and in such collapsed condition the ornament may be packed at low cost without the necessity of exercising any undue care, the ornament being non-breakable and occupying very little space and being thus capable of being shipped, and mailed if desired, at low cost. The ornament may be marketed without the exercise of the caution and care as is the case in prior ornaments of this kind; and the ornament may 90 be sold in bulk in a very convenient manner. When desired for decorative use the user merely separates or "opens up" the surface sections and the ornament will assume the three dimensional configurations 95 shown in Figures 5, 7, 9 and 10 of the drawings. When the ornament is suspended on a Christmas tree or other structure, a variegated display which is highly pleasing to the observer is provided. At the end of the 100 holiday season the ornaments may be removed and the parts collapsed and stored in collapsed condition until the next Christmas holiday. The ornament may be made in any of a variety of forms to assume any 105 desired configuration of a three dimensional object and may be sold suitable to the taste of the dealer and the purchaser.

While I have shown my device in the preferred forms, it will be obvious that many 110 changes and modifications may be made in the structure disclosed without departing from the spirit of the invention, defined in the following claims.

I claim:

1. A new article of manufacture for use 115 as a Christmas tree decoration or the like comprising an ornament including a plurality of surface sections, means connecting said sections to permit the latter to be movable relatively to each other to positions circumferentially spaced about a common axis to assume a three dimensional configuration, the said sections being movable from such positions to collapsed condition.

2. A new article of manufacture for use 120 as a Christmas tree decoration or the like comprising an ornament including a plurality of surface sections, connecting means for said sections, the said surface sections 125 130

being movable relatively to each other to positions circumferentially spaced about a common axis to assume a three dimensional configuration and maintainable in such positions by said connecting means, the said sections being movable to collapsed condition.

3. A pendant ornament including a plurality of surface sections, each section including a lune portion of a sphere or the like, means connecting said sections, the said means comprising provisions connecting the sections at opposed portions of the same, the said surface sections being movable relatively to each other and positionable about a common axis including the said provisions, the surface sections being positionable about such axis to assume a three dimensional configuration and being movable from such positions to collapsed condition.

20 4. A new article of manufacture for use as a Christmas tree decoration or the like comprising an ornament including a plurality of similar symmetrical surface sections, means pivotally connecting opposite ends of said sections, the said sections being pivotally movable into overlying relation to collapsed condition and from such collapsed condition to spaced positions to assume a three dimensional configuration, the said sections being movable about a common axis.

5. A new article of manufacture for use as a Christmas tree decoration or the like comprising an ornament including a plurality of surface sections, means connecting said sections to permit the latter to be movable relatively to each other to positions circumferentially spaced about a common axis to assume a three dimensional configuration, the said sections being movable from such positions to collapsed condition, said surface sections providing colored reflecting faces.

45 6. A pendant ornament including a plurality of surface sections, each section including a lune portion of a sphere or the like, means connecting said sections, the said means comprising provisions connecting the sections at opposed portions of the same, the said surface sections being movable relatively to each other and positionable about a common axis including the said provisions, the surface sections being positionable about such axis to assume a three dimensional configuration and being movable from such positions to collapsed condition, said surface sections being made of flexible material and providing colored reflecting faces.

60 7. A pendant ornament including a plurality of surface sections, each section including a lune portion of a sphere or the like, means connecting said sections, the said means comprising provisions connecting the sections at opposed portions of the same, the said surface sections being movable rela-

tively to each other and positionable about a common axis including the said provisions, the surface sections being positionable about such axis to assume a three dimensional configuration and being movable from such positions to collapsed condition, the said surface sections providing different colored faces effecting a variegated ornament display.

75 8. A new article of manufacture for use as a Christmas tree decoration or the like comprising an ornament including a plurality of surface sections, means connecting said sections to permit the latter to be movable relatively to each other and positionable about a common axis to assume a three dimensional configuration, the said sections being movable from such positions to collapsed condition, said surface sections including metallic foil faces.

80 9. A pendant ornament including a plurality of surface sections, each section including a lune portion of a sphere or the like, means connecting said sections, the said means comprising provisions connecting the sections at opposed portions of the same, the said surface sections being movable relatively to each other and positionable about a common axis including the said provisions, the surface sections being positionable about such axis to assume a three dimensional configuration and being movable from such positions to collapsed condition, the said surface sections including metallic colored foil faces, adjacent sections being differently colored to provide a variegated ornament display.

95 10. A new article of manufacture for use as a Christmas tree decoration or the like comprising an ornament including a plurality of surface sections, each section including a lune portion of a three dimensional surface, connecting means for said sections; the said means comprising provisions connecting the sections at opposite portions thereof, the said surface sections being positionable relatively to each other about a common axis to assume a three dimensional configuration and maintainable in such positions by said connecting means, the said sections being movable to collapsed condition.

105 11. A pendant ornament including a plurality of separable surface sections, means connecting said sections, the said means including a suspending element threaded through opposed portions of the sections, the said surface sections being movable relatively to each other circumferentially about the said connecting means to spaced positions to assume a three dimensional configuration and being movable from such positions to collapsed condition.

110 12. A pendant ornament including a plurality of separable surface sections, means connecting said sections, the said means in-

cluding a suspending element threaded through opposed portions of the sections, the said surface sections being movable relatively to each other about the said connecting means to spaced positions to assume a three dimensional configuration and being movable from such positions to collapsed

condition, the said surface sections being made of flexible material faced with colored metallic foil.

Signed at New York city in the county of New York and State of New York this 31st day of December, A. D. 1921.

GERHARDT E. GRIMM.
